GRINDING MACHINE

Owen Doutt, Detroit, Mich., assignor, by mesne assignments, to General Spring Bumper Corporation, a corporation of Michigan

Application September 6, 1927. Serial No. 217,599

12 Claims. (Cl. 51—100)

This invention relates to apparatus for use in grinding, polishing or buffing and more particularly to a machine for finishing vehicle bumper bars or similar articles. In the following description and claims the operation will be referred to as one of grinding and the machine as a grinder but it is not intended to thereby limit the invention to use in a grinding operation since it is apparent that by merely replacing the grinding element by a polishing or buffing element the operations of polishing and buffing could be performed by the same machine. The general object of the invention is to provide means by which several bars may be ground at the same time, and over their entire exposed surface, without manual handling of the individual bars.

A further object of the invention is to provide a carrier upon which the bumper bars may be placed and which may be passed as a unit through a series of operations resulting in the complete grinding, polishing or buffing of the surfaces of the bars.

Further objects of the invention are to provide means for regulating the height of the carriage for use with grinding wheels of different diameters and means for independently regulating the pressure of the several bars upon the grinding element and so allowing for irregularities in the bars.

Other objects are to provide means for resiliently supporting said bars at their intermediate and end portions and novel means for fastening the ends of said bars.

Further objects are to provide means for conveying the carriage from one grinder to another, whereby the curved ends and the flat surfaces of the bumper may be successively ground, and to provide means for controlling the direction of movement of the carriage so as to allow movement in directions at right angles to each other.

A further object is to provide means for reciprocating the carriage through an arc whereby the curved surfaces of the end portions of the bars will be oscillated in contact with the grinding element. Further objects are to provide novel means for connecting and detaching the carriage from the reciprocating driver and means for controlling the movement of the latter.

A further object is to provide means for moving the carriage during the operation of grinding the flat surfaces of the bars.

Further and more limited objects will be apparent from the drawings, from the following description and from the use of the combination of elements covered by the appended claims.

Drawings

In the drawings Fig. 1 represents a diagrammatic plan view of an arrangement of four grinders and four carriers whereby the curved and flat surfaces of the bars may be ground in succession; Fig. 2 shows a side elevation of a grinder with the reciprocating device attached thereto; Fig. 3 shows a side elevation of a carriage with one of the height regulating tubes and one of the wheel pivots shown in section; Fig. 4 is a side elevation of a carriage and an end elevation of a grinder for grinding the curved ends of the bars; Fig. 5 shows a view similar to Fig. 4 in which the carriage is advanced and the grinding wheel is in contact with curved surfaces of the bars; Fig. 6 shows a detail view of the end of the grinder and a portion of the side of the carriage with the latter partially advanced; Fig. 7 represents a plan view of a carriage with the bars removed; Fig. 8 shows a side elevation of a carriage and an end elevation of a grinder adapted to grind the flat surfaces of the bumper bars; Fig. 9 is a fractional detailed elevation taken from the position indicated by line 9—9 of Fig. 3 and showing the mechanism provided to grip the reciprocating member; Fig. 10 is a sectional view taken on line 10—10 of Fig. 9; Fig. 11 is a sectional view taken on line 11—11 of Fig. 9; Fig. 12 is a plan view of the lower portion of the carrier with sections through the tubular raising mechanisms; Fig. 13 is an elevation taken from the position indicated by line 13—13 of Fig. 8 and showing in detail the means for fastening the ends of the bars; Fig. 14 is an end elevation of the view shown in Fig. 13; Fig. 15 is a side elevation of the view shown in Fig. 13, looking from the left side of that figure; Fig. 16 shows a fractional detail plan view of the means provided for supporting the bars; Fig. 17 shows a fractional detail view of mechanism for advancing the carriage under the flat surface grinder.

Description

Of the reference characters shown in the several views, 1, 2, 3 and 4 denote diagrammatic representations of four carriers each loaded with nine bars and positioned at different stages of the series of operations. The carrier 1 is positioned so as to permit grinding of the curved end portions of the bars at the right-hand end of the carrier by contacting them with the grinding element 9 of the grinder 5. The grinder 5 is made up of a motor 10, a rotatable shaft 11 upon which the grinding element 9 is fixed, and

a shaft 12 for supporting the outer end of the shaft 11, as will be explained more in detail hereinafter. The carrier 2 is positioned to have the curved ends of the bars at the left-hand end 5 of the carrier ground by the grinding element of the grinder 6, which is of the same type as the grinder indicated at 5 and like parts of which are designated by like numerals. The carrier 3 is in a position to start the grinding operation 10 upon the flat surfaces of the bars, by passing them successively under the grinding elements of the grinders 7 and 8. The carrier 4 is shown in its position after the grinding of the flat surfaces of the bars. These figures are merely diagrammatic of the several stages contemplated and the details of the reciprocating and translating mechanisms have been omitted.

As shown in Fig. 2 the shaft 11 is supported by bearings in the uprights 13 and 14 and by the 20 arm 14^a clamped to the shaft 12 by means of the clamp 15. The shaft 12 is supported at its inner end by the uprights 13 and 14. Fixed to the shaft 11 is a pulley 16^a which, together with the shoe 16^b, actuated by the springs 16^c and the lever 16^d, acts as a brake by which the grinder wheel 9 may be stopped when the power is 25 shut off.

The bars to be ground, indicated at 16, are each supported at their central portions upon plungers 17, resiliently mounted in blocks 18 which are supported in substantially vertical positions upon the vertically adjustable table 19. The end portions of the bars 16 are supported upon plungers 17 resiliently mounted in the blocks 20 30 which are supported upon the table 19 at a suitable angle to the vertical.

The table 19 is raised and lowered by means of supporting devices at the ends of the table, each of which includes a screw shaft 21 (Fig. 3) 35 threaded into a plate 22 rigidly connected to the inner surface of a hollow cylindrical post 23. The shaft 21 is rotatably supported at its lower end upon a bearing plate 24 and has fixed thereto a beveled gear 25. This beveled gear is actuated by a beveled gear 26 fixed to a shaft 27 which may be rotated by a hand wheel 28. The cylindrical post 23 has a slotted aperture 29 to receive a mounting 30 supporting and adapted to contain the shaft 27. The post 23 is slidably telescopied within a cylindrical post 31 which is fastened to the bearing plate 24 and has an aperture 32 to receive the mounting 30 and the shaft 27. A cylindrical dust cap 33 is fixed to a collar 34 and positioned to surround the upper portion 50 of the cylindrical post 31. By turning the hand wheel 28 the threaded shafts 21 are rotated and the plates 22, the cylindrical posts 23, the collars 34, the dust caps 33 and the table 19 are thereby raised or lowered as desired, depending 55 upon the direction of rotation of the hand wheel 28.

As is shown more clearly in Fig. 12 the cylindrical posts 31 are supported upon cross members 35 which are in turn supported at their end portions by four wheels 36. The wheels 36 are mounted upon axles 37 (Fig. 3) which are supported from saddles 38 affixed to vertical shafts 39. The 90° bell cranks 40 are fixed to the shafts 39 and each is connected to the bell crank at the 60 opposite side of the same end of the carrier by means of a link 41, and to that at the opposite end on the same side by means of a link 42. The links 41 and 42 are each pivotally connected at their ends to parallel lever arms of the bell cranks 75 40. With the arrangement of bell cranks shown

a longitudinal movement of the links 42 will simultaneously change the direction of all four wheels 36 through an angle of 90°. A spring 43 is connected between the links 42 in order to maintain the wheels in the desired direction until it is intended that their direction should be changed. In arranging the links for use with the spring 43, the links 42 should be on the outside of the shafts 39 in order that the movement of the bell cranks will cause separation of the links 42 and a tension upon the spring 43. 80

Rotatably attached to the ends of each of the blocks 20 are rollers 44 which are adapted to support the ends of the carriage when the curved ends of the bars are being ground. Each of the rollers 44 has a guide 45 thereon and as the carriage is advanced to the position shown in Fig. 4 the forward rollers will roll upon the upper flat surfaces of two templates 46, one at each side of the carriage. The templates 46 are each adjustably mounted upon a support 47 by means of a slidable connection within a slot 48 and are controlled by screws 49. Each template 46 has a flat surface 50 which changes to an arc 51 by which the movement of the forward end of the 100 carriage will be directed so as to permit contact between the curved end portions of the bars 16 and the grinding wheel throughout the length of the arc of such curved portions. By suitably designing the surface 51, bars having end portions 105 of different shapes may be ground upon my machine. By regulating the position of the templates 46 allowance may be made for variations in the thicknesses of the bars or for differences in the diameters of the grinding wheels. 110

At each end of the carriage there is provided a suitable clamping device adapted to grip a rod 52 carried by a reciprocating link 53, to be described more in detail hereinafter. This gripping means consists of a stationary hook 54 fastened to the side of the block 20 and having a recess 55 (Figs. 9 and 10) for the reception of the rod 52. Cooperating with said hook 54 is a movable plate 56 slidably attached, by means of notched plates 57 and bolts 58, to the block 20. 115 Springs 59 hold the plate 56 against the plate 54. Levers 60, which are pivotally connected at 61 to opposite sides of the plate 56 and pivotally connected at 62 to a lever 63 fixed to a shaft 64, operate the plate 56 against the pressure of the 120 springs 59. A lever 65 is fixed to the shaft 64 and by moving that lever the plate 56 can be moved downward to allow the rod 52 to enter the recess 55. The plate 56 can then be moved upward to prevent the removal of the rod 52 from 125 the recess 55. The surfaces 66 and 67 (Fig. 10) of the plates 54 and 56, respectively, are inclined to aid in directing the rod 52 into the recess 55. 130

The mechanism for reciprocating the carriage 135 is clearly shown in Figs. 2 and 6. A motor 70, through a shaft 71, a transmission 72 and a ratchet wheel 73, rotates a disk 74. A link 75 is pivotally connected at 76 to the disk 74, at a point spaced from the center of said disk. The 140 other end of the link 75 is pivotally connected to a lever 77 at 78. The lever 77 is pivotally supported upon a pin 79, carried by arms 80 which are attached to the upright 13 through the webbed bracket 80^a. The link 53 is pivotally connected at 81 to the lower end of the lever 77. The rod 52 is adjustably connected to the end of the link 53 by means of a turn buckle 82. The rod 53 is movably supported by means of a collar 83 around said rod and a rod 84 pivotally connected 145 to the link 53. The rod 84 is pivotally supported by a collar 85 around the rod 53 and is connected to the 150

nected thereto and passing through an aperture in a pivot bolt 85. The nuts 86 threaded upon the rod 84 limit the downward movement of the lever 53 and are so placed as to allow the rod 52 to move downward and out of the recess 55 when the plate 56 is withdrawn.

The clutch for operating the reciprocating mechanism includes a disk 73 keyed to the shaft 71 and having notches 87 in its periphery, and a bell crank 88 pivotally supported at 89 upon the disk 74. The bell crank has a projection 90 adapted to fit within any of the notches 87 and a spring 91 between a pin 92 and the bell crank 88 holds the bell crank normally in such a position that the projection 90 is within a notch 87. The disk 74 which is free to rotate on shaft 21 will, by means of bell crank 88, be made to move with that shaft. A pin 93 is slidably supported in the support 94 so that a projecting portion 95 may be withdrawn to allow the passage of the lower end of the bell crank 88. When the pin 93 is moved to the position shown in Fig. 2 it will engage the bell crank 88 and so disconnect the disk 74 from the disk 73 and the former disk will idle on the shaft 71. When the end of the pin 93 is removed, the pressure of the spring 91 will cause the projection 90 to engage a notch 87 and the disk 74 will be rotated with the shaft 71.

Each of the blocks 18 and 20 are bored out, as shown more clearly in Fig. 10, for the reception of the bottom portions of the plungers 17. A shoulder 97 on each plunger 17 bears upon a closure plate 98 which surrounds each plunger and is bolted to the block by bolts 102. Springs 99 resiliently hold each plunger 17 in its extended position with the shoulder 97 against the plate 98. Guards 100 and 101 of leather or other suitable material, surround the plungers 17 and prevent dirt from getting into the joint between the plungers 17 and the plates 98. As shown in Fig. 16 the plates 98 are cut at an angle to allow greater space between the bolts 102. By the arrangement shown, each of the plungers may be individually removed for any necessary attention.

As shown in Figs. 8, 13, 14 and 15, the ends of the bars 16, having eyes 103, may be fastened to the plungers 17 by means of a bracket 104 and a pin 105. The bracket 104 is here shown as made up of a plate having its ends turned up to form projections 106. Portions intermediate the ends of the plate are cut out and turned up to form projections 107, spaced to fit between the bars 16. Plates 108 are riveted to the projections 106 and are adapted to extend around the outer plungers 17 and to terminate at points between the two outer plungers at each end of the blocks 20. Pins 109, retained by suitable cotter pins, pass through apertures in the opposite portions of the plate 108 and in the outside plungers 17 and retain the bracket 104 in its proper position. The pin 105 passes through suitable apertures in the projections 106 and 107 and through the eyes 103 in the ends of the bars and thereby holds the bars 16 in position on the plungers 17. One end of the pin 105 is shown as bent at 110 to form a handle and to provide an extension adapted to fit, and be retained, between spring members 111 and 112. Such fastening means may be used at both or either of the ends of the bars.

In Figs. 8 and 17, there is shown a mechanism suitable for moving the carriage under the grinding element of a grinder adapted to operate upon the flat surfaces of the bars. A rack 113, hav-

ing teeth 114 on its undersurface, is fastened to the cross members 35 of the carriage. A gear 115 is rotatably mounted on a pin 116 supported in standards 117. A shaft 118, supported at its ends at 119 and 120, has fixed thereto a pulley 122 and a gear 121 adapted to mesh with the gear 115. The shaft 118 may be driven by a belt 123 on the pulley 122 and the carriage will be advanced under the grinding element 9 by the action of the gear 115 on the rack 113.

85

Operation

The bars 16 are placed on the plungers 17 and the ends may be fastened by means of the pin 105 and the bracket 104. A wheel 9 of suitable abrasive or buffing qualities is fixed to the shaft 11 and suitable templates 46 are adjusted by the screws 49 to give the desired movement of the end of the carriage so that the curved surfaces of the ends of the bars will contact with the grinding element. The carriage is advanced until the rod 52 moves into the notch 55 and the clamp is then closed by means of a lever 65. The end 95 of the pin 93 is withdrawn and the projection 90 on the bell crank 88 is allowed to enter one of the notches 87 of the rotating disk 73. The reciprocating motion of the carriage may be continued until the desired amount of grinding or buffing is completed. The pin 93 may then be moved to actuate the bell crank 88 and free the disk 74. The bell crank and the pin 93 should be so positioned that the motion of the rod 52 will stop at the top of its stroke. Suitable electromagnetic braking means may be applied to the shaft 71 to facilitate the stopping at the desired point.

The carriage may then be moved to the position indicated at 2 of Fig. 1 and the curved surfaces at the other ends of the bars may be ground. After the second operation the lever 42 is moved longitudinally to rotate the wheels 36 through an angle of 90° and the carriage is moved to a point opposite the grinding element of the grinders 7 and 8. The wheels are then moved back to their original position and the carriage is moved forward so that the gear 115 will contact with the teeth of the rack 113. The bars may then be drawn under one or more grinders to give the desired finish to the flat surfaces of the bars and they may then be removed from the carriage. If desired, grinding, polishing or buffing elements of different abrasive qualities may be used to produce successively a grinding, polishing and a buffing action.

Each of the curved or straight bar grinding operations may be performed without the other and although it is desired that the operations be carried out in the order named, my invention is not limited to such a combination, it being apparent that at times it may be desired to only polish curved or flat surfaces of the bars. It is further apparent that the particular means shown for reciprocating the carriage or for translating the same are not essential to my invention.

The individual support means for the bars 16 will permit the simultaneous grinding of a plurality of bars of different thickness and a uniform grinding of bars of varying thickness throughout their length, but my invention is not confined to the particular supporting means herein shown. I have described a means for fastening the ends of the bumper bars to the carriage but it is apparent that other means may be substituted for those shown. It is also contemplated that bars fastened together in a uni-

tary structure as they are often handled in electroplating may be applied to and supported upon my carriage without removing them from the racks used for that purpose.

5. It is also apparent that other means for moving the carriage to the desired positions and in the desired directions might be substituted without avoiding the scope of my invention.

In order to give a complete disclosure I have 10 described in detail a preferred embodiment of my invention and an application of the same but it is not intended to thereby limit the scope of the invention to those elements or applications specifically shown and described since it is apparent 15 that my invention in its broader scope may be applied to mechanisms differing greatly in detail from the constructions shown.

Having thus described my invention, what I claim is:—

20 1. The combination with a grinding element, of a carriage adapted to support work to be ground, said carriage having a roller adapted to support an end of the carriage and to guide the movement thereof over a predetermined path by its contact with a template, and having a grip adapted to grasp the free end of a reciprocating mechanism, said mechanism including a lever fulcrumed intermediate its ends and having a connecting rod pivoted to one end, which connecting rod is pivotally connected at its other end to a crank arm driven by a rotatable shaft, and a link pivoted at the other end of the fulcrumed lever and having a free end adapted to be removably retained by said grip, which link is of 30 adjustable length and is retained in the desired raised position by a rod slidably connected to the fulcrumed lever for adjustable limited movement relative thereto.

25 2. The combination with a grinding element, of a carriage adapted to support work to be ground, said carriage having a roller adapted to support an end of the carriage and to guide the movement thereof over a predetermined path by its contact with a template, and having a grip adapted to grasp the free end of a reciprocating mechanism, said mechanism including a lever fulcrumed intermediate its ends and having a connecting rod pivoted to one end, which connecting rod is pivotally connected at its other end to a crank arm free to rotate on a drive shaft and adapted to be driven by said shaft through a pivoted bell crank having a projection at one end adapted to fit in one of the notches of a ratchet wheel fixed to the drive shaft and having an arm at the other end adapted to engage a removable stop whereby the projection may be withdrawn from the notch, and a link pivoted at the other end of the fulcrumed lever and having a free end adapted to be removably retained by said grip.

30 3. The combination with a grinding element, of a carriage adapted to resiliently and individually support a plurality of bars having curved ends to be ground, said carriage having adjustable supports for regulating the height of the bars and having four wheels, each of which is adapted to rotate on a horizontal axle carried by a shaft pivotally connected to the carriage frame and having a 90° bell crank fixed to its upper end in such a position that when the wheels are all turned in the same direction the two bell cranks on one side of the carriage will have their arms parallel and each extending outward at an angle of approximately 45° to a lateral line through its shaft, and the two bell

35 cranks on the other side of the carriage so positioned that their arms are parallel and each extend at an angle of about 45° from a longitudinal line through the shafts thereof, a lever at each end of the carriage extending laterally and pivotally connected at its ends to parallel crank arms, said levers being on the same relative side of the shafts to which the crank arms are connected, a lever on each side of the carriage extending longitudinally and pivotally connected to the remaining parallel arms of the cranks in such a manner that the longitudinally extending levers will move away from each other as the wheels are turned from one position to another, and a spring connecting said longitudinally extending levers and adapted to resist outward movement thereof.

4. The combination with a grinding element and a carriage adapted to resiliently and separately support a plurality of bumper bars having eyes at their ends, of means for retaining said bars upon said resilient supports, said means comprising brackets supported from the carriage and having projecting portions extending between the eyes of said bars, and a pin having a 100 diameter less than that of said eyes adapted to pass through the eyes at one end of the carriage and apertures through the projecting portions of said bracket.

5. A grinding machine including, a grinding 105 element, driving means for rotating the same, a carriage for supporting a curved piece of work in operative relation to said grinding element, said carriage including spring pressed plungers for supporting said work, said carriage being 110 mounted on rollers, other rollers carried by said carriage at at least one end, a template for guiding said curved work into grinding relation with said grinding element, said other rollers at one end only of said carriage adapted to cooperate 115 with said template.

6. A grinding machine including a grinding element for grinding a curved end portion of a piece of work, a carriage including angularly related spring-pressed plungers for supporting said work 120 in proper operative relation to said element, said curved portion having means cooperating with said plungers whereby said piece of work is retained on said carriage.

7. A grinding machine including a grinding 125 element, a carriage, a support for said carriage and grinding element, said support having an opening adjacent said grinding element, said carriage being movable along the support on rollers, means providing for pivotal movement of said carriage 130 for grinding a curved piece of work, said means being operative to support one end of the carriage when said end is disposed over said opening, said means including a template whereby said end of the carriage may dip and rise in a predetermined path to provide for grinding of the curved surface of the piece of work, and instrumentalities for reciprocating the said end of the carriage along said template.

8. A machine for grinding a curved piece of 140 work, said machine including a grinding element, driving means for rotating the same, and a carriage including angularly related spring pressed plungers for supporting said work in proper operative relation to said element.

9. The combination with a grinding element and a work feeder adapted to translate a bar across the surface of said grinding element, of means for progressing said bar with said work feeder, said means comprising a spring for yield- 145

- ably resisting longitudinal movement of said bar relative to said work feeder.
10. Apparatus for grinding a metal bar having an offset portion on one end thereof comprising a grinding wheel, a carrier, an outwardly-extending presser arm on said carrier, having means thereon for engaging said offset portion, a second presser arm projecting outwardly and affording support for another portion of the bar, and means for yieldably holding said arms in projected position.
11. Apparatus for grinding curved bumper bars having eye portions formed in each end thereof, comprising a grinding wheel, a conveyor, presser arms carried by said conveyor and having means for effecting detachable connection with the ends
- of said bar, and means for yieldably urging said presser arms outwardly to hold the bar against the grinding wheel during traveling movement of the conveyor.
12. Apparatus for grinding curved bumper bars having eye portions formed in each end thereof, comprising a grinding wheel, a conveyor, presser arms carried by said conveyor and having means for effecting detachable connection with the ends of said bar, an arm intermediate the first-named arm, and means for yieldably urging said presser arms outwardly to hold the bar against the grinding wheel during traveling movement of the conveyor.
